UNITED STATES PATENT OFFICE.

FRANK E. FISHER, OF DETROIT, MICHIGAN.

ENGINE-STARTER.

1,288,549.

Specification of Letters Patent. Patented Dec. 24, 1918.

Application filed January 10, 1918. Serial No. 211,135.

To all whom it may concern:

Be it known that I, FRANK E. FISHER, citizen of the United States, residing at Detroit, county of Wayne, State of Michigan, 5 have invented a certain new and useful Improvement in Engine-Starters, and declare the following to be a full, clear, and exact description of the same, such as will enable others skilled in the art to which it pertains 10 to make and use the same, reference being had to the accompanying drawings, which form a part of this specification.

My invention relates to a combined engine starter and lighting generator and is particularly designed for automobiles employing 15 an internal combustion engine as a motive power.

In apparatus of this character it is customary to provide a train of gears including 20 an automatic engaging and releasing clutch between the armature shaft of the motor and the armature shaft of the generator, the latter being permanently connected by a driving sprocket chain or other gearing 25 with the crank-shaft of the engine;—the armature shaft of the generator when driven by the motor serving only to actuate the sprocket chain or gearing carried by and connecting it with the crank shaft of the 30 engine to start the latter.

Coincident with the operation of the engine under its own power, the driving connection between the armature shaft of the motor and the armature shaft of the generator is severed through the automatic operation 35 of a clutch mechanism.

It has been found in practice, however, 40 that the driving chain connection between the armature shaft of the generator and the crank-shaft of the engine is frequently broken in devices of this character, due to the lash occurring from what is known as “backfiring” of the engine.

It is therefore one of the objects of this 45 invention to provide means adapted to yieldingly absorb the shock produced by “backfiring” while “cranking” the engine.

With the foregoing and other objects in view which will appear as the description 50 proceeds, the invention resides in the combination and arrangement of parts herein-after described and claimed; it being understood that changes may be made in the precise embodiment of the invention herein disclosed without departing from the spirit of the same.

In the drawings accompanying this specification:—

Figure 1 is a vertical sectional view through a combined starting motor and 60 lighting generator unit.

Fig. 2 is an end elevation of the same, showing the driving gear connection, and the shock absorbing means between the armature shaft of the motor and the armature shaft of the generator. 65

Fig. 3 is a side elevation of one of the gears indicated in the preceding view, with a portion broken away to indicate further details of construction. 70

Fig. 4 is an elevation of the gear shown in Fig. 3 taken at right angles thereto, with parts in section.

Fig. 5 is an end elevation of a starting motor and generator unit, showing a driving 75 chain connection with the crank-shaft of an engine.

Fig. 6 is a detail perspective view illustrating the construction of the arched wheel and the tilting pawl. 80

Referring now to the letters of reference placed upon the drawings:—

A, denotes an inclosing case housing a starting motor B, and a lighting and recharging generator C. 85

D, indicates the commutator of the motor; E, its armature, and F, the armature shaft journaled in ball-bearings F', F', carried by the frame.

G, designates a pinion on the shaft F, in 90 mesh with a gear H, loosely mounted upon the hub I', of a pinion I, in turn carried by a stub shaft J, journaled in the frame.

Between the periphery of the hub I', and the gear H, is an annular chamber H', 95 formed by the side wall h, of the gear and a removable annular ring h', encircling the hub,—spaced from the side wall h, but attached to the gear.

P, P, are pins secured in the hub I', projecting radially therefrom into the annular chamber H, and in diametrically opposite directions. 100

Q, Q, are pins projecting transversely through the annular chamber supported by 105 the side wall of the gear and the annular ring secured to the latter.

S, S, indicate springs lodged in the annular channel the respective ends of which bear against the pins P, and Q. 110

The pinion I, meshes with a floating gear X, loosely mounted on the hub of a ratchet

wheel L, keyed to the shaft M, of the generator. The gear K, comprises two members bolted together to provide a central chamber between its side-walls adapted to receive a 5 tilting pawl N, to engage the ratchet wheel L.

The pawl N, is fitted with a rocker arm N', to which is engaged a yielding band spring O, encircling the hub a, of the frame 10 in which the shaft M, is journaled.

T, denotes a driving chain connection between the sprocket wheel T', carried by the armature shaft M, of the generator C, and the sprocket wheel T², on the crank-shaft 15 U, of the engine.

Having indicated the several parts by reference letters the construction and operation of the device will be readily understood.

As previously indicated it is customary in devices of this character to provide a permanent driving connection T, between the generator shaft and the crank-shaft of the engine. To start the engine the motor is 20 first energized in the usual manner which through the train of gears and clutch mechanism actuates the generator shaft and thereby operates the driving chain connection between it and the crank-shaft of the 25 engine.

Upon the engine operating under its own power, at a relatively higher speed, the clutch mechanism automatically releases the driving connection between the generator and 30 motor shafts in a manner well understood in this art.

It will now be seen that if upon attempting to start the engine it should "back fire" the shock caused thereby will be absorbed 35 by the springs S, S, which admit of a slight yieldable rotary movement of the gear H, upon the hub I,—thus relieving the driving chain of the strain that might otherwise break it. It will also be noted that in the 40 cranking action of the device the pins P and Q will engage one another and afford an unyielding means for rotating the crank shaft in a forward direction.

Having thus described my invention what 45 I claim is:

1. In a device of the character described, in combination with an internal combustion engine and its crank-shaft; an electric motor, an electric generator, a train of gears 50 providing a driving connection between the

armature shaft of the motor and the armature shaft of the generator, a driving connection between the armature shaft of the generator and the crank-shaft of the engine, having unyielding means for rotating the 60 crank shaft in a forward direction, and resilient means adapted to absorb the shock upon the driving connection resulting from a "back fire" of the engine.

2. In a device of the character described, 65 in combination with an internal combustion engine and its crank-shaft; an electric motor, an electric generator, a driving chain connection between the armature shaft of the generator and the crank-shaft of the 70 engine, and a train of gears connecting the armature shaft of the motor with the armature shaft of the generator, said train of gears including a rotatably resilient gear wheel, adapted to sustain a driving connection between the coöperating gear wheels of 75 said train of gears, and to recoil sufficiently to relieve the shock upon the driving chain connection due to "back firing" of the engine, said resilient gear wheel having unyielding means for rotating the crank shaft 80 in a forward direction.

3. In a device of the character described, 85 in combination with an internal combustion engine and its crank-shaft; an electric motor, an electric generator, a driving chain connection between the armature shaft of the generator and the crank-shaft of the engine, a train of gears connecting the armature shaft of the motor with the armature 90 shaft of the generator, said train of gears including a pinion having a projecting hub, an annular gear having flanges fitted over said hub forming an annular chamber between the hub and gear, pins carried by the 95 hub projecting radially into said annular chamber, pins supported by the flanges of the gear extending transversely through the annular chamber, and helical springs lodged in the annular chamber and bearing against 100 one of the radial and one of the transverse pins, said pins being also adapted for rotating the crank shaft in a forward direction.

In testimony whereof, I sign this specification in the presence of two witnesses.

FRANK E. FISHER.
